MICHAEL KUCSERA, OF NEW YORK, N. Y.

INTERNAL-COMBUSTION ENGINE.

1,121,850.

Specification of Letters Patent. Patented Dec. 22, 1914.

Application filed September 8, 1909. Serial No. 516,700.

To all whom it may concern:

Be it known that I, MICHAEL KUCSERA, a subject of the King of Hungary, and resident of the city of New York, in the county 5 of New York and State of New York, have invented certain new and useful Improvements in Internal-Combustion Engines, of which the following is a specification.

The present invention relates to internal 10 combustion engines, and has for its object to provide an engine in which the combustible charge, or one or both of its constituents, are heated by the hot exhaust gases, the heat of which is ordinarily lost in the 15 operation of an internal combustion engine.

Other objects of the invention will be apparent in reading the specification and from an examination of the drawings, forming part of the present application for Letters 20 Patent.

With these objects in view, the invention consists, broadly speaking, of an engine having one or more passages leading from the supply-chamber of the combustible mixture, 25 or from the supply chamber of one of its constituents, to the inlet port of the cylinder of the engine, which passages are arranged in close contact with a passage leading from the exhaust port or ports to a muffler or the 30 atmosphere, whereby all or some of the heat of the exhaust gases is imparted to the entering fresh charge, raising thus its temperature.

One of the many possible embodiments of 35 the invention is illustrated in the drawings, in which—

Figure 1 is a central vertical section of an engine embodying the invention, Fig. 2 a section taken on line 2, 2 of Fig. 1, Fig. 3 40 is a front elevation of the engine, part of the shell being broken away in order to more clearly show the construction, Fig. 4 is a section taken on line 4, 4 of Fig. 2, Fig. 5 is a vertical section of an engine embodying 45 a modified construction of the invention, Fig. 6 illustrates a detail of another modification, and Fig. 7 is a section taken on line 7, 7 of Fig. 6.

In the drawings, the numeral 8 indicates 50 a water cooled cylinder, having the usual water-jacket 9. The cylinder 8 is mounted upon a crank-case 10, substantially circular in form and provided with removable side pieces 11, which allow of a proper assembling of the movable parts of the engine. 55 The crank-case and the side pieces 11 form

bearings in which the crankshaft 12 is journaled. The crankshaft is connected by a pitman 13 to a piston 14 of the usual type and construction; its deflector being indicated 60 at 15, and serving a well known purpose. The piston controls the intake 10' of the crank-case.

In opposite sides of the cylinder are arranged the inlet port 16 and the exhaust 65 port 17, each of which extends almost over half of the periphery of the cylinder and are, therefore, provided with bridges 18 and 19, respectively, to make the structure more rigid. The exhaust port 17 communicates 70 with a chamber 20, which in turn is connected to a muffler 21 of any suitable construction, or may communicate with the atmosphere. In the crank-case, and more particularly on the exhaust side thereof, is arranged 75 a substantially vertical passage 22, leading toward the chamber 20 and branching just below it into two passages 23, 23, which lead to the two sections of the inlet 16 of the cylinder. The upper wall of the 80 passage 23 and the bottom of the chamber 20 are common, whereby the heat given up to the walls of the chamber 20, is conducted into the passage 23, heating thereby the fresh combustible charge and completing 85 thus the evaporation of the fuel.

It is, of course, understood that the invention may be applied to all kinds of internal combustion engines, irrespective of their mode of operation and construction, and 90 irrespective of the number and arrangement of their cylinders.

A modification of the invention is shown in Fig. 5, in which the communicating passage between the crank-case and the inlet of 95 the engine is located outside of the crank-case. In this particular case the inlet 24 and the outlet 25 are arranged upon the same side of the cylinder, and more particularly the exhaust port above the inlet port. A 100 pipe 26 leads from the exhaust port and is bent downward substantially parallel with the axis of the cylinder. A communicating passage 27 leads from the outlet 28 of the crank-case to the inlet 24 of the cylinder and is arranged in the exhaust pipe 26. The piston 28' of the engine is provided with a deflector 29, which forms with the top 30 of the piston a passage 31, through which the 105 fresh charge is admitted into the cylinder.

The operation of the heating means of 110 the fresh charge is obvious. Instead of ar-

ranging the communicating passage 27 in the exhaust pipe; the same may be arranged outside thereof, as for instance shown in Figs. 6 and 7, in which a pipe 32 is provided having two passages, that is passage 33 for the exhaust gases and passage 34 for the fresh charge. Of course, instead of casting the two passages in one pipe, two separate pipes may be provided, the walls whereof contact with each other.

While the communicating passage is herein described as conveying the combustible mixture to the cylinder of the engine, it will be understood that the same may serve to carry only one of the constituents of the charge to the inlet port.

What I claim is:

1. In an internal combustion engine, the combination of a cylinder having a suction port, an inlet port in its wall and opening with their inner sides into the cylinder, an exhaust port opposite the inlet port, a duct leading from the compression chamber upon the exhaust side, adjacent to the exhaust port, where it branches and extends around opposite side of the cylinder and communicates with the explosion chamber through the said inlet, the arrangement being such that the contents of the branch ducts and partly of the main duct will be heated by the hot exhaust gases discharged through the exhaust port.

2. In an internal combustion engine, the combination of a cylinder, having an inlet port and exhaust port, each one extending partly around the cylinder and forming a channel on the inner side of suction port communicating with the compression chamber, a duct leading from the compression chamber upon the exhaust side adjacent to the exhaust port, where it branches and extends around opposite side of the cylinder and communicates with the explosion chamber through the said inlet, the arrangement being such that the contents of the said ducts will be heated by the hot exhaust gases discharged through the exhaust port.

3. In an internal combustion engine, the combination of a cylinder having an inlet port opening with their inner side into the cylinder and an exhaust port extending

partly around the cylinder, a suction port communicating with the compression chamber, a duct leading from the compression chamber upon the exhaust side adjacent to the exhaust port, branching around opposite side of the cylinder and communicating with the explosion chamber through the said inlet, the arrangement being such that the contents of the branch ducts and partly in the main duct will be heated by the hot exhaust gases discharged through the exhaust port.

4. In an internal combustion engine, the combination of a cylinder having a suction port, and an inlet port opening with their inner sides into the cylinder, and suction port communicating with the compression chamber, a duct leading from the compression chamber upon the exhaust side adjacent to the exhaust port and branching around the opposite side of the cylinder and communicating with the explosion chamber through the said inlet, the exhaust port and the branch ducts having a common wall, the contents of the branch ducts and partly that in the main duct will be heated by the hot exhaust gases discharged through the exhaust port.

5. In an internal combustion engine, the combination of a cylinder having one or more inlet ports, one or more exhaust ports, each one extending partly around the cylinder, opposite to each other, sectioned with bridges, opening with their inner side into the cylinder suction port communicating with the compression chamber, ducts leading from the compression chamber upon the exhaust sides adjacent to the exhaust ports and branching around opposite side of the cylinder, and communicating with the explosion chamber through the said inlet ports, the arrangement being such that the contents of the said ducts will be heated by the hot exhaust gases discharged through the exhaust ports.

Signed at New York, in the county of New York and State of New York, this 31st day of August, A. D. 1909.

MICHAEL KUCSERA.
